UNITED STATES PATENT OFFICE.

HARRY THOMASMA AND ADDISON H. BLANCHARD, OF GRAND RAPIDS, MICHIGAN.

DESIGN FOR A BROOM-HEAD.

52,813.

Specification for Design.

Patented Dec. 24, 1918.

Application filed August 4, 1914. Serial No. 855,074. Term of patent 3½ years.

To all whom it may concern:

Be it known that we, HARRY THOMASMA and ADDISON H. BLANCHARD, citizens of the United States, and residents of Grand Rapids, in the county of Kent and State of Michigan, have invented a certain new, original, and ornamental Design for Broom-Heads, of which the following is a specification, which, taken in connection with the accompanying drawing, fully discloses the design that others may understand the same.

In the drawing:

The figure shows in front elevation our design for a broom-head.

We claim:

The ornamental design for a broom head substantially as shown.

In testimony whereof we have hereunto affixed our signatures in the presence of a witness.

HARRY THOMASMA.
ADDISON H. BLANCHARD.

Witness:

H. H. YARRINGTON.
